(57) **CLAIM**

I claim the ornamental design for a door stop, as shown and described.

DESCRIPTION

The door stop is a versatile device that can be: (1) positioned on the door hinge, (2) wedge underneath the door, (3) positioned on the width of the door, or (4) wedged into the top corner of an open door; to provide an easy and efficient way to stop and retain a door in an open position.

FIG. 1 is a perspective view of the door stop being positioned on the width of the door.

FIG. 2 is a perspective view of the door stop being positioned on the hinge of the door.

FIG. 3 is a side view of the door stop being wedged into the top corner of an open door;

FIG. 4 is a perspective view of the door stop being wedged underneath the door.

FIG. 5 is a bottom view of the door stop.

FIG. 6 is a top view of the door stop.

FIG. 7 is the front view of the door stop.

FIG. 8 is the back view of the door stop.

FIG. 9 is a side view of the door stop; and,

FIG. 10 is the other side view of the door stop.

The broken lines in FIGS. 1, 2, 3, and 4 displaying a door, door hinge, and door frame are for illustrative purposes only and form no part of the claimed design.
